CHILD'S FEEDING DISH OR SIMILAR ARTICLE

Robert V. Rhodes, 1185 Hillcrest Ave., Pasadena, Calif.

Filed June 28, 1963, Ser. No. 75,574

Term of patent 14 years

(CL. D44—15)

Fig. 1

Fig. 3

FIG. 1 is a top plan view of a child's feeding dish, showing my new design;

FIG. 2 is a sectional view taken on line 2—2 of FIG. 1; and

FIG. 3 is a sectional view taken on line 3—3 of FIG. 1. I claim:

The ornamental design for a child's feeding dish or similar article, as shown.
